UNITED STATES PATENT OFFICE.

FRANK KEACH RUSSELL, OF DALLAS, TEXAS.

EMBOSSING-MACHINE.

SPECIFICATION forming part of Letters Patent No. 709,422, dated September 16, 1902.

Application filed January 3, 1901. Serial No. 41,995. (No model.)

To all whom it may concern:

Be it known that I, FRANK KEACH RUSSELL, a citizen of the United States, residing at Dallas, in the county of Dallas and State of Texas, have invented certain new and useful Improvements in Embossing-Machines; and I do declare the following to be a full, clear, and exact description of the invention, such as will enable others skilled in the art to which it appertains to make and use the same.

The invention relates to embossing-machines, and more particularly to those used by saddle-makers for stamping leather.

The object of the invention is to provide a machine of the character described wherein the impression-rolls are mounted in a novel manner, so that shorter curves may be embossed without the dragging or tearing effect common with the usual means now in use.

A further object is to provide a machine of this character which shall be simple of construction, durable in use, and comparatively inexpensive of production.

To these ends the invention consists in the features of construction and novel combination and arrangement of parts hereinafter described, and then more particularly set forth in the claims following this specification.

In the accompanying drawings, Figure 1 is a side view of my improved embossing-machine. Fig. 2 is a vertical longitudinal sectional view through the same. Fig. 3 is a detail view, on an enlarged scale, showing the relative arrangement of one of the roll-shafts, its gear, and the crank and its meshing gear. Fig. 4 is a sectional view taken on the line $x-x$ of Fig. 1. Fig. 5 is a detail sectional view through one of the impression-rolls and its shaft.

Referring now more particularly to the drawings, 1 denotes the frame of the machine, which may be a casting of any desired shape or configuration; 2, the throat of the machine; 3, the upper set of bearings of the upper roll-shaft; 4, the lower set of bearings of the lower roll-shaft; 5, the upper roll-shaft, and 6 the lower roll-shaft. The upper roll-shaft 5 has mounted on its forward end a series of impression-rolls 7 and 7^a, which may be of any desired number and the surfaces of which may be provided with any form of design or configuration. The center roll 7 of the series

is formed with a key, which is adapted to engage a keyway 5^a in the forward end of the shaft 5, thereby locking said roll to said shaft, 55 so as to positively drive said roll upon rotation of the shaft 5. This roll acts as a feed-roll to the material being operated upon. The rolls 7^a of the series are loosely mounted upon the shaft 5 and turn only by frictional 60 contact with the material. The object of thus mounting the impression-rolls is to prevent any undue tearing or dragging of the material when working around short curves or turns in the same, which would be the case 65 if the rolls were all positively driven. The lower roll-shaft has fixed upon its forward end a wide bearing-roll 7^b, which coacts with the upper feed-roll 7 and also presses the material against the upper series of impression- 70 rolls. The rear end of the roll-shaft 5 has fixed to it a bevel gear-wheel 8 and a plain gear-wheel 9, while the rear roll-shaft 6 has fixed to it a plain gear 10, which meshes with the gear 9 on the shaft 5.

11 denotes a bearing fixed to the rear end of the supporting-frame, and 12 denotes a crank-shaft journaled in said bearing and projecting rearwardly and arranged at an angle of about one hundred and five degrees to 80 the shafts 5 and 6 and provided with a gear-pinion 13, in mesh with the gear-wheel 8 of the shaft 5. The crank may be provided with an operating-handle 14. It will be noticed that by the rotation of said crank motion will 85 be imparted to the shafts 5 and 6, and as the rolls are fixed to said shafts they will operate upon the material in the usual manner. The main feature of this part of my invention is the arrangement of the crank-shaft 12 at an 90 obtuse angle to the shafts 5 and 6, whereby said shafts may be more conveniently rotated than if the crank were secured directly to the end of one of said shafts.

Another feature of my invention resides in the manner of forcing one of the rolls toward the other roll in working on leather or metal. To this end I mount the rear end of the shaft 6 in a bearing 15, which will permit of a slight rocking movement of said shaft at its rear 100 end. The forward end of the shaft is mounted in a bearing-box 16, supported to have a vertical movement between guideways 17, cast integral with the frame of the machine.

A treadle or lever 19 is fixed to a lug 19', depending from the frame, and has a bill 20, which is adapted to engage a pin 21, extending downwardly from the box 16 and designed when the treadle or lever is actuated in one direction to elevate said bearing-box 16, and thus force the lower roll toward the upper roll. When the pressure is removed from the lever or treadle, the lower roll drops to its normal position. It is of course understood that while the movement of the forward end of the shaft 6 is sufficient to accomplish the desired result the movement of the rear end of the shaft is so slight as not to disengage the teeth of the gear-wheel 10 from the teeth of the gear-wheel 9 on the shaft 5.

From the foregoing description, taken in connection with the accompanying drawings, the construction and mode of operation of my improved embossing-machine will be readily understood without a more extended explanation of the same.

Various changes in the form, proportion, and minor details of construction may be made within the scope of the invention without departing from the spirit or sacrificing any of the advantages thereof.

Having thus described my invention, what I claim, and desire to secure by Letters Patent, is—

1. In a machine of the character described, the combination of upper and lower geared

roll-shafts and means for rotating the same, of a series of impression-rolls mounted upon said upper roll-shaft, the center one of which being fixedly mounted thereon and the rest loosely mounted thereon, a bearing or pressure roll fixed on said lower roll-shaft and adapted to bear upon said impression-rolls, and means for regulating the pressure of said bearing or pressure roll, substantially as and for the purpose described.

2. In an embossing-machine provided with a suitable frame and upper and lower geared roll-shafts mounted therein; a series of impression-rolls mounted upon said upper roll-shaft, the center one of which being fixedly mounted thereon and the rest loosely mounted thereon whereby in making curved figures upon leather or other material the roll or rolls between the center of the figures or impressions and said fixed roll will be permitted to run slower than the fixed roll and the roll or rolls outside of the fixed roll will be permitted to run faster than said fixed roll, a suitable bearing mounted on the lower roll-shaft, and means for operating the machine.

In testimony whereof I have hereunto set my hand in presence of two subscribing witnesses.

FRANK KEACH RUSSELL.
